UNITED STATES PATENT OFFICE.

ZEALIE VAN RAALTE, OF NEW YORK, N. Y.

DESIGN FOR NET VEILING.

46,067.

Specification for Design.

Patented July 7, 1914.

Application filed May 8, 1914. Serial No. 837,345. Term of patent 3½ years.

To all whom it may concern:

Be it known that I, ZEALIE VAN RAALTE, a citizen of the United States, and a resident of the city of New York, county of New York, and State of New York, and whose post-office address is 100 Fifth avenue, in said city, have invented a new and original and ornamental Design for Net Veilings, of which the following is a specification.

Reference is to be had to the accompanying drawing, in which the figure is a plan view of a section of the fabric showing my new design.

I claim:

The ornamental design for a net veiling as shown herein.

Signed at the city of New York, county of New York, and State of New York, this 6th day of May, 1914.

ZEALIE VAN RAALTE.

Witnesses:

EDWIN C. ANDERSON,
ERNEST SCHACHT.
